DEPHLEGMATING APPARATUS

Application filed June 28, 1920. Serial No. 392,476.

Our invention relates to a dephlegmating apparatus for the control of the rate of pressure distillation in cracking processes.

Our invention provides an apparatus for the pressure distillation of heavy hydrocarbon oils to produce light oils therefrom, by means of a series of hydrocarbon vapor outlets from a dephlegmator; to provide an apparatus of a dephlegmation system of pressure distillation of heavy hydrocarbon oils, so that one or more streams may be taken off the pressure still simultaneously; to provide an apparatus in which the rate of pressure distillation is controlled by means of the dephlegmation system; to provide an apparatus of pressure distillation in which the dephlegmation system is flexible, so that sections of said dephlegmation system may be reduced or increased from the maximum and minimum area of said dephlegmator.

The following description covers the apparatus as shown in drawing:

Number 1, is a fuel burner set within furnace number 2 and tunnel number 2—a to stack not shown. Number 3, is a high pressure still with man-hole plate number 4, with pipe connection number 5 attached to dephlegmator number 6, having baffle plates number 7 set therein. Number 8, is a conduit attached to dephlegmator number 6, having valve number 9 with conduit number 10 connected with piping number 11. Connections number 12, 15 and 18 are attached to dephlegmator number 6, having valves number 13, 16 and 19 set therein, connected with pipes number 14, 17 and 20 connected with piping number 11. Numbers 9—a, 13—a, 16—a and 19—a are chains which control valves number 9, 13, 16 and 19. Number 32 having inverted dish number 33 set within dephlegmator number 6 is a trap for the dephlegmated oil, which is condensed in said dephlegmator number 6, so that it will pass via piping number 34 into the bottom of high pressure still number 3. Condenser coil number 21, attached to piping number 11, is set within condenser box number 22. To condenser number 21, receiver number 23 for the pressure distillate oil is attached, having pipe number 24 and control valve number

25 for releasing pressure distillate oil in said receiver number 23, through pipe connection number 26, to storage tank not shown. Number 27 is a gage level glass for determining the height of liquid in receiver number 23. Number 28 is uncondensable gas pipe connected with control valve number 29 to pipe number 30, which is connected with uncondensable storage gas tank not shown.

A typical method of operation of this apparatus is to charge the high pressure still number 3 with a Midcontinent gas oil of 32.0 Baumé gravity. Valve number 9 attached to conduits number 8 and 10 are opened while valves number 13, 16 and 19 are closed. The uncondensable gas control valve number 29 and pressure distillate oil valve number 25 are closed. Burner number 1, is ignited, and the products of combustion in furnace number 2 heat up oil in still number 3 until the generated vapors from said hydrocarbon oil charge, self-impress a pressure upon the entire system of usually 100 pounds to the square inch. This pressure is not a fixed one as it depends largely upon the type oil to be cracked as to what pressure of self-generated vapor from hydrocarbon oil is to be used within the system. When a high pressure still 8 ft. in diameter and 30 feet long is used and charged with 8,000 gallons hydrocarbon oil, it may take 20 hours to pressure distill 55 percent of said charge, producing a 51.0 gravity pressure distillate oil. During this 20 hour period of pressure distillation many fluctuations of atmospheric condition may take place, such as sudden drops of temperature, high winds, rain or snow storms which profoundly modify the activity of the dephlegmation system. We have found that during a high wind period to pressure distil the hydrocarbon oil it is necessary to fire the still very hard or maintain a high furnace temperature so as to overcome the rapidity of radiation of heat from the dephlegmator. The fluctuation in pressure distillation during a 20 hour period may range from 100-400 gallons per hour. To overcome this, we have invented an apparatus which during high winds and storms can be so modified that sections of the dephlegmating system can be 100

cut out or added as weather conditions modify.

We have further found that hydrocarbon oils of different characteristics such as a Midcontinent gas oil, a Kansas fuel oil, such as from the Augusta field or the Wayside field or a Pine Island gas oil for a fixed pressure still, each require different degrees of dephlegmation for equivalent cracking and gasoline production. When cracking hydrocarbon oils such as Wayside or Augusta fuel oils, the amount of aerial condensation or dephlegmation required is much less than when using gas oils from the same crudes.

When cracking said fuel oils, we have found it advisable to cut out the parts of dephlegmator number 6, which are controlled by closing valves number 9, 13 and 16 so that the hydrocarbon vapors generated from the pressure distillation of said fuel oils pass out via pipe number 18, valve number 19, pipe number 20 connected with piping number 11, condensing in coil number 21, passing to receiver number 23.

Now when cracking a Midcontinent gas oil and quiet weather conditions are at hand, dephlegmation system is used by closing valves number 13, 16 and 19 and opening valve number 9, however when wind condition is intense, valve number 9 is closed and valve number 13 opened while valves number 16 and 19 are closed which provides us with a flexible dephlegmating system to take care of the type oil to be cracked during inclement weather conditions which is the crux of our invention. Heretofore there has been in use as far as we know, only a fixed dephlegmation system for a fixed still to handle various types of hydrocarbon oils and varying weather conditions.

We do not limit ourselves to the particular design as shown in the drawing of a vertical dephlegmator with baffle plates therein, but believe it comes within the scope of our invention to include a horizontal or a series of horizontal dephlegmators connected with one another by piping taking off a stream of pressure distillate from each horizontal dephlegmator controlled by valves so as to add or deduct dephlegmating surface from the dephlegmating system.

We claim as our invention:

In an apparatus for cracking hydrocarbon oils, a vertically elongated dephlegmator, having a series of baffles therein vertically disposed with respect to each other, a vapor inlet at the bottom of said dephlegmator, a liquid outlet adjacent the bottom of said dephlegmator, means for preventing liquid from passing out through said vapor inlet, a plurality of vertically spaced vapor outlet conduits communicating with said dephlegmating column intermediate the baffles therein, independently operable valves positioned in said conduits, to control the passage of

vapors through said conduits and permit taking off of the vapors through any desired conduit, and means for maintaining a super-atmospheric pressure on the vapors in the dephlegmator.
